UNITED STATES PATENT OFFICE.

MANIOUS GARL, OF AKRON, OHIO.

FIRE-ALARM-TELEGRAPH SYSTEM.

No. 867,494.

Specification of Letters Patent.

Patented Oct. 1, 1907.

Application filed October 20, 1905. Serial No. 283,626.

To all whom it may concern:

Be it known that I, MANIOUS GARL, a citizen of the United States of America, and a resident of Akron, in the county of Summit and State of Ohio, have invented 5 certain new and useful Improvements in Fire-Alarm-Telegraph Systems, of which the following is a specification.

My invention relates to improvements in magneto-electric fire-alarm telegraphy, and has for its object the 10 simplification of the system of apparatus employed, the increase of its efficiency and the reduction of cost there-of and expense of operation.

Hitherto, in fire-alarm telegraphy or other analogous systems, the common means for operating the apparatus 15 has comprised main and numerous local batteries; all of which are subject to deterioration and require frequent attention and renewal.

In the improved system herein disclosed, I have altogether eliminated the use of batteries, which by their 20 nature are ill-adapted for transmission over long circuits, and have employed instead, the magneto-electric generator for operating the system; arranging and adapting the apparatus of said system in such manner as to be operated more efficiently thereby.

25 Details of the improved system of my invention will be more readily gathered by making reference to the accompanying drawings, illustrating an embodiment and apparatus of my invention, wherein;

Figure I. is a pictorial diagram, showing a system of 30 fire-alarm telegraph, equipped in accordance with my invention; and, Fig. II. shows in perspective, two improved relays of my invention, adapted for use therein and diagrammatically connected to be employed alternatively.

35 The same character of reference has been used throughout the drawings to indicate similar parts and thereby avoid confusion.

In the diagram of Fig. I, the central station and alarm apparatus for the fire-alarm telegraphic circuit, comprising in this instance, but two call-boxes, is sufficiently set forth to explain the features of my improvement. At the central station are the power magnetos M and M', adapted alternatively to supply current for the system, the tape register T, the relays R, R', and the auxiliary 40 testing, switching and alarm apparatus. Connected in circuit at any practicable distance from the station are the alarm or call-boxes C, C'; these registering respectively "15" and "14". It will be observed that no batteries whatsoever are associated with this circuit, and 45 that all the electric power is derived from one or the other of the magnetos M, M', which are alternatively driven at such relatively high rate of speed as to impress currents upon the line, of sufficient frequency of alternation to act upon the controlling relay and retain it normally 50 inoperative. This current is transmitted over the line through the several call-boxes and returns by metallic

circuit to the central office. The alarms, however, are primarily transmitted over grounded circuits, temporarily opening the normal metallic circuit of the system. This in turn deenergizes the controlling-relay R or R', 60 and causes it to close a local alarm circuit. Said relays are constructed to respond to alternating-currents; having their windings connected respectively between binding-posts e' or e'', and the frames of said relays. The frames are respectively connected to binding-posts 65 e and e', and also serve as "grounds" for the local circuit, adapted to be closed between screws r' and springs r'', when the controlling-relay is deenergized. This best appears in the diagrammatic representation of Fig. II. Assuming then that magneto M is being employed 70 to operate the system, it will be seen that the normal circuit is traced from its left side over conductor 1, through call-boxes C, C', and any others that may be connected serially in circuit, over conductor 2, through the windings of relay R, and conductors 3, 4 and 5 to 75 the opposite terminal of the magneto. This will serve normally to excite the relay, causing its armature mounting r, to assume the vertical position shown in the drawings and maintain its contact screw r', out of engagement with the spring r'', controlling the circuit 80 to the alarm apparatus. When an alarm is sent in, however, which in my improved apparatus is transmitted by releasing the weight e' of box C', the toothed actuating wheel c' will engage the spring c'; depressing it to disengage the upper contact-spring and at the same 85 time make a wiping contact with the grounding spring c'', intermittently during the rotation of said wheel and thereby transmitting the signal "14" to the central office over the grounded circuit thus momentarily established.

As before, current may be traced from the left hand pole of magneto M, conductor 1 to box C' over its ground connection G to the ground G' of tape register T, through its electro-magnet t, connected between binding-posts i, i', and conductors 4 and 5 to the other 90 pole of the magneto. Current also flows to the ground G', the alarm bell A, and conductor 5 to the magneto. This serves to strike upon said alarm bell and to register upon the tape t', the signal "14", to indicate the box from which the alarm is turned in. Similarly, 100 during the opening of the metallic circuit conductor 2, relay R will be deenergized, thus causing its armature mounting to assume the position shown with respect to relay R', and closing the local circuit through the central station alarm bells A', A'', at contact r'' and sounding 105 thereon as well, the signal "14". This circuit may be traced from the left hand pole of magneto M, conductor 6, through the bells A', A'' in multiple, conductor 7, spring r'', contact-screw r' to the frame of the relay, binding-post e, and conductors 3, 4 and 5 to the opposite pole of the magneto.

The several switches s⁴ to s⁹ are respectively shown

- open and closed for establishing the respective circuits above set forth, but they may readily be changed in an obvious manner, to connect the other relay R' in circuit, should the same become desirable or necessary.
- 5 The several alarm bells A, A' and A² will, of course, be positioned at the central station, at the office of the chief of police, and in the appropriate engine house, or elsewhere as the needs of the particular system shall dictate.
- 10 Duplicate power magnetos and controlling relays are provided merely for the purpose of avoiding a breakdown of the service, in case any one of these is incapacitated for use. Moreover, it will be seen that the alarms may be sent in to the tape register and bell A over the grounded circuit, irrespective of the condition of the metallic circuit 2.
- 15 There remain to be described merely, the operation of the testing-switch S and certain features with respect to the preferred apparatus employed on circuit 20 in practicing my invention. This testing-switch is equipped with contact arms s' and s³, respectively adapted to ground one or the other of the poles, either of magneto M or M', through the extension-bell E, to test the condition of the system, while the central contact-arm s² short-circuits the two grounding-plates for arms s', s³, or it may be connected for other testing purposes. Thus, if there be an accidental ground upon either side of the metallic line, the depression of the corresponding arm will serve to close the grounded extension-bell circuit, and ring bell E, while short-circuiting the operating magneto will permit the controlling-relay to engage its local-circuit contacts. As for example, if there be a ground upon line 2, the depression of arm s³ will close a circuit from the ground of extension bell E through said bell, the arm s³, the conductor extending to the right, through conductors 4, 5, magneto M, and conductors 1, 2, to the assumed accidental ground. The foregoing features, I may say, however, form no part of my present invention, and are briefly 35 set forth herein only to outline the workings of a practical signal telegraph system.
- 40 The magnetos, which I employ, may well be wound to 50,000 ohms, and being power driven, are sufficiently strong individually to force rapidly alternating currents over lines of extreme length, and those presenting conditions which would make battery transmission impracticable or impossible.

The relays, the electro-magnet for the tape register, and the loud-ringing alarm bells may be wound to 50 1,000 ohms; while a 500 ohm bell E is sufficient for testing.

Certain mechanical features indicated in the drawings, which I believe to be of importance, are the effective wiping-contact arrangement, secured for the 55 springs in the alarm boxes, the spring printing-arm t² provided upon the tape register, and the peculiar form of relay above set forth.

The spring contact-arm t² takes up the slight vibration present in the armature of the tape register, under

the influence of alternating currents and insures a continuous mark, during the intermittent periods of magnetic excitation, corresponding to the separate impulses of the transmitted signal. 60

The relay armature r³ is pivotally mounted by means of brass side pieces r⁴ upon the magnet poles r⁵. Under the influence of alternating currents, the armature is drawn into the position indicated by relay R, thereby by bridging the magnetic gap between the pole pieces r⁶, and normally separating the contacts r' and r². 65

It will now be appreciated how I have dispensed with separate sources of direct current in fire-alarm telegraphs, and have employed a constantly-running magneto-generator of rapidly alternating currents, which generator is more efficient and cheaper in operating the system disclosed, than any other with which 70 I am acquainted.

It will now be appreciated how I have dispensed with separate sources of direct current in fire-alarm telegraphs, and have employed a constantly-running magneto-generator of rapidly alternating currents, which generator is more efficient and cheaper in operating the system disclosed, than any other with which 75 I am acquainted.

The foregoing details relating to the practical application of my improvement, and the apparatus above set forth, of course, are not necessary to the invention herein claimed; it being my desire and intention to 80 protect by separate applications, the patentable features above referred to.

Accordingly, I claim herein, and desire to secure by Letters Patent, together with such modification as may be made by mere skill, the following:—

85 1. In a fire alarm telegraph system, a normally closed line circuit, alarm transmitting appliances connected therein, a normally open ground circuit, suitable alarm apparatus therein, and a normally open local alarm circuit, said local circuit being closed by the breaking of the line circuit, and said ground circuit being closed and opened alternately with said line circuit.

2. In a fire alarm telegraph system, a single source of current, a normally closed line circuit, alarm transmitting appliances connected therein, a normally open ground circuit, suitable alarm apparatus therein, and a normally open local alarm circuit, said local circuit being closed by the breaking of the line circuit, said ground circuit being closed and opened alternately with said line circuit, and all of said circuits being energized by said single source of current. 95

3. In a fire alarm telegraph system, a constantly driven generator of alternating current, a normally closed line circuit, alarm transmitting appliances connected therein, a normally open ground circuit, suitable alarm apparatus therein, and a normally open local alarm circuit, said local circuit being closed by the breaking of the line circuit, said ground circuit being closed and opened alternately with said line circuit, and all of said circuits being energized by said generator. 105

4. In a fire alarm telegraph system, a constantly driven generator of alternating current, a normally closed line circuit, alarm transmitting appliances connected therein, a normally open ground circuit, suitable alarm apparatus therein, a local alarm circuit, and a relay in said line circuit controlling said local alarm circuit to normally maintain the latter open, said ground circuit being closed and opened alternately with said line circuit, and all of said circuits being energized by said single source of current. 115

Signed at Akron, Ohio, this 18th day of October, 1905, 120 A. D., in the presence of two subscribing witnesses.

MANIOUS GARL.
